UNITED STATES PATENT OFFICE

130,149

DESIGN FOR A BATTERY CHARGER CASE

John H. Kolseth, Newark, N. J., assignor to Atlas Supply Company, Newark, N. J., a corporation of Delaware

Application July 30, 1941, Serial No. 102,573

Term of patent 3½ years

To all whom it may concern:

Be it known that I, John H. Kolseth, a citizen of the United States, residing at Newark, in the county of Essex and State of New Jersey, have invented a new, original, and ornamental Design for Battery Charger Cases, of which the following is a specification, reference being had to the accompanying drawings, forming part thereof.

In the drawings:

Fig. 1 is a perspective view of a battery charger case showing my new design.

Fig. 2 is a rear elevational view.

Fig. 3 is a side elevational view, and

Fig. 4 is a top plan view.

The dominant features of my design reside in the portions shown in full lines.

I claim:

The ornamental design for a battery charger case, as shown and described.

JOHN H. KOLSETH.
